UNITED STATES PATENT OFFICE

132,852

DESIGN FOR A PROJECTOR

Gustave Fassin, Ann Arbor, Mich.

Application November 10, 1941, Serial No. 104,101

Term of patent 14 years

To all whom it may concern:

Be it known that I, Gustave Fassin, a citizen of the United States, residing at Ann Arbor, in the county of Washtenaw and State of Michigan, have invented a new, original, and ornamental Design for a Projector, of which the following is a specification, reference being had to the accompanying drawing, forming a part thereof.

Figure 1 is a side elevational view of a projector, showing my new design;

Figure 2 is a top plan view thereof; and Figure 3 is a front elevational view of the same. The essential features of my design for a projector reside in the portions shown in full lines.

I claim:

The ornamental design for a projector, substantially as shown and described.

GUSTAVE FASSIN.
